UNITED STATES PATENT OFFICE

JULIUS BRENDLE, OF ZURICH, SWITZERLAND

TIME-RECORDING INSTRUMENT

Application filed January 24, 1925, Serial No. 4,523, and in Switzerland May 24, 1924.

The present invention relates to improvements in time-recording instruments.

In order to avoid the subsequent calculation of the effective working time when checking the latter by means of a time-recording instrument the drive of the indicating device formed by the time operated type wheels or stamping mechanism is interrupted during those intervals in the working time which 10 are not counted as over-time.

To this end the recording instrument is provided with an auxiliary device by which a device for imparting actuating motion to the type wheels is automatically cut out and is 15 only cut in again when the interval not to be recorded has elapsed.

The indicating device on time-recording instruments forming the subject matter of the present invention is provided with a type 20 wheel driven by a wheel-work, the type wheel carrying a scale for indicating time units which takes into account the intervals in the working time so that the type wheel indicates directly the effective working time.

25 The indicating scale of the type wheel may be so arranged that it indicates the effective time when being actuated by a continuously working clock work. Thereby the above mentioned auxiliary device for cutting the type wheel in and out is rendered superfluous as well as a separate device for actuating the type wheel, and the recording instrument is thus substantially simplified and the costs of manufacture are correspondingly reduced.

30 In a modified constructional example of the indicating device a further stamping or type organ may be provided besides the type wheel, which stamping organ carries an indicating scale for time units that is different from the scale of the type wheel, a pawl and ratchet mechanism having a wheel provided with a toothing that takes into account the intervals in the working time cooperating 40 with the stamping organ for adjusting the latter into the stamping positions. Provision is further made that the type organ returns into its initial position by the toothing of the ratchet wheel, whilst during the intervals in 45 the working time the stamping organ is pre-

vented from being further displaced and remains in its proper stamping position.

The scales on the type wheel and on the stamping organ may, for instance, be such that one scale unit on the type wheel corresponds to one tenth of an hour and one scale unit on the type organ corresponds to one hundredth of an hour so that it is also possible to obtain very accurate indications of the time elapsed during a comparatively 55 short working process.

The invention will now be explained with reference to the accompanying drawings in which several constructional examples of the time indicating device according to the present invention are illustrated. In these drawings:

Fig. 1 shows in elevation the type wheel and the parts adapted to drive the type wheel.

fied mechanism for imparting rotation to a type wheel,

Fig. 16 shows a time indicating device comprising a type wheel and a further type organ in an elevation view, the type wheel being omitted,

Fig. 17 is a plan view of Fig. 16,

Fig. 18 is a detail of Fig. 16 and

Fig. 19 shows in a diagrammatic manner a modified arrangement for driving a type organ of the type shown in Figs. 17 and 18.

Referring now to the constructional example illustrated in Figs. 1-3 1 denotes the type wheel which is fixed to the shaft 2 by means of a milled screw nut 3 cooperating with the end 4 of the shaft provided with screw thread.

Between the plates 5 and 6 of the instrument a clockwork is mounted consisting of the usual rotatably mounted casing 7 which encloses the spiral spring and is provided with a toothed rim 8. A train of gear wheels 9, 10, 11, 12, 13, 14 and 15 is interposed between the toothed rim 8 of the casing and the escapement wheel 16 with which the stops 17, 18 on the pendulum 19 cooperate.

To the shaft 2 carrying the type wheel 1 a gear wheel 20 is fixed for driving the type wheel. To this end a second spring operated mechanism is provided consisting of a spring casing 21 provided with a toothed rim 22 which is in mesh with the gear wheel 20. The rotating movement of the type wheel 1 has to be effected intermittently for reasons stated hereinafter and in order to control this movement of the type wheel 1 a gear wheel 23 is in mesh with the gear wheel 20 on the shaft 2 of the type wheel 1, the gear wheel 23 acts normally as a stop and prevents the rotation of the gear wheel 20 under the urge of the spring casing 21. The gear wheel 23 is operatively connected by means of a train of gears 24, 25, 26 and 27 to a two-winged blade 28 fixed to the axle 29 on which the gear wheel 27 is secured (Figs. 1 and 3). The tips of the blade 28 cooperate with a gear wheel 30 secured to the axle 31 on which the gear wheel 12 which forms part of the train of gear wheels of the clockwork is secured.

The gear wheel 30 is provided with six teeth and will perform one complete revolution during a determined time. The tip of a wing 28 which is pressed against the teeth of the wheel 30 by the action of the spring casing 21 glides off the flank of a tooth of the wheel 30 when the latter assumes a determined angular position, whereupon the blade 28 performs half of one revolution and the tip of the other wing engages with the next tooth of the wheel 30 and so forth. Every time the blade turns through one half of a revolution the type wheel is turned through a determined angular extent. On the axle 29 a gear wheel 32 is mounted which cooperates with a

gear wheel 33 to the axle 34 of pallet 35 for preventing an excess speed.

The type wheel 1 is provided at its circumference with an indicating scale consisting of printing types which will now be explained with reference to Fig. 4 and Figs. 10-12. This scale indicating time units starts at I with 00 which corresponds to the beginning of the working hours, for instance to 7 o'clock a.m. To the numbers 00 follow in the direction of the arrow the numbers 05, 10, 15, 20 and so on up to 55 and then 100. The angular extent between 00 and 100 corresponds to one working hour, the intermediate numbers indicate the minutes. After the number 100 the row of numbers starts again with 05 up to 55 and 200 which corresponds to two working hours. In a similar manner the time scale is continued so that at II the number 500 will be present, which corresponds to five working hours. This scale is continued at III, when the row of numbers starts again with 05, 10 and so on up to the number 600 which corresponds to six working hours. The numbering is repeated in a similar manner up to IV where the number 900 is present which corresponds to nine working hours and which represents the normal daily working time in the chosen example.

The parts of the circumference of the type wheel situated between II and III and between IV and I, which interrupt the scale of the type wheel correspond to the intervals in the working, which with the type wheels illustrated in Fig. 1 and in Figs. 4, 10, corresponds to one hour for the part II-III and to two hours for the part IV-I. Thereby it is assumed that the type wheel performs one complete revolution during 12 hours and the gear wheel 30 controlling the step by step turning movement of the type wheel performs one complete revolution every half hour so that every five minutes a turning impulse acts on the type wheel 1. Obviously the type wheel 1 may also perform one complete revolution within 18 or 24 hours whereby the time scale would have to be altered accordingly; the printing types might be arranged to indicate tenths of hours.

The scale may, however, also be continued between IV and I and eventually also between II and III and the figures on the printing types in these intervals may be combined with symbols to distinguish the indications by these parts of the type wheel as overtime. For instance a "+" symbol may be added to these figures as is illustrated in Fig. 11 at A and B.

The above described type wheel is intended for indicating the working time of an ordinary working day. With other working times, as, for instance, is the case on Saturdays, another type wheel the scale of which corresponds to the different working time is required. The scale of a "Saturday" wheel

70

130

is shown in Fig. 12 and the printing types range from 00 up to 500 to indicate five working hours. The remainder of the circumference of the Saturday-wheel designated with C is left blank. In order to obtain a continuous record of the working hours during one week six type wheels are required, one for each working day. A day-type wheel has to be exchanged after the day has elapsed 10 against the type wheel having the consecutive scale.

The type wheel illustrated in Figs. 4 and 5 consists of a rim 36 carried on arms and to one side of the rim are shaped portions or segments 37, 38, 39 and 40 are screwed. The portions 37 and 39 are provided at their circumference with the scale of time units described above as the parts I to II and III to IV. The portions 38 and 40 correspond to the intervals in the working time; the portion 38 and eventually the portion 40 may also be omitted, in case no symbols for marking over-time are provided as has been described with reference to Fig. 11 when over-time has not 25 to be registered.

The arc shaped portions 37—40 may be exchanged with other portions having a different scale if it be desired, the screw connection permitting a convenient exchange.

In order to vary the scale indicating working time units, i. e. the printing types, on the type wheel itself, the latter may be provided with exchangeable printing types as is illustrated in the constructional example shown 35 in Figs. 6-9. The type wheel shown in section in Fig. 6 comprises two discs 41 and 42. The disc 41, one half of which is shown in Fig. 8 when looking at its inner side, is rigidly fixed on the shaft 2. The disc 42, 40 one half of which is illustrated in Fig. 8 is detachably connected to the disc 41 by means of three set-screws 43 which engage sockets 44 provided on the disc 41 and having internal thread. The discs 41 and 42 45 are provided with laterally extending flanges 45 and 46 adjacent to their outer peripheries and the disc 42 carries a further flange 47 concentric to the flange 46. The flange 46 is provided with a plurality of equally pitched 50 radial notches 48 adapted to receive a printing type 49. The individual printing type 49 which is securely held in between the two discs 41 and 42 has a head portion 50 projecting beyond the circumference of the discs 55 41 and 42 and a foot portion 51. The latter is enlarged in the lateral direction in the shape of a hammer head and the printing types rest with the end of the foot on the flange 47 and with the shoulders of the hammer head on the flanges 45 and 46 respectively. In the lateral direction the printing types 49 bear against the discs 41 and 42 with the ends of the hammer head and in the circumferential direction of the discs the portions of the printing types projecting beyond 60

the circumference of the discs 41 and 42 bear against each other (Fig. 9) and the printing types are embedded in the radial notches 48. The printing types are thus non-displaceably held in position.

These printing types may be readily exchanged and the scale indicating the units of the working time may thus be adapted to any subdivision of the working time. In order to exchange printing types the screws 70 43 are unscrewed and the disc 46 together with the printing types 49 are removed from the shaft 2. The variation of the scale indicating the working time may also be effected by means of type wheels which are angularly adjustable one against the other. An embodiment of this type is illustrated in Figs. 13 and 14. Three type wheels 52, 53 and 54 are arranged beside each other on the shaft 2 and it is assumed that the type wheels are 75 provided with time indicating scales in such a manner that the type wheel 52 indicates five working hours which correspond to the working time on a forenoon and is provided with printing types bearing the figures 00 80

up to 500, as has been described above for the part I-II of the type wheel shown in Fig. 4, and a blank circumferential space equal to at least two hours being provided. The type wheel 53 carries printing types having the figures 500 up to 900 corresponding to the working time on an afternoon, and a blank space equal to three hours and the type wheel 54 carries printing types having a symbol besides the figures to indicate over-time, the figures starting with 00 up to say 400, the rest of the circumference of the wheel being left blank. The intervals in the working time are obtained by a corresponding angular displacement of the end of the scale on the wheel 52 against the beginning of the scale on the wheel 53 and when the intervals change the adjustment of the wheels is varied accordingly. In Fig. 13 55 denotes the tray on which the cards, on which the working time derived from the indicating means is printed, are placed and 56 is the hammer of the known mechanism which causes the cards to be pressed against the printing type of the type wheel. In Fig. 13 it is assumed that the hammer 56 is laterally displaceable, in one position it cooperates with the normal working time type wheels 52 and 53, in the other position the hammer cooperates with the type wheel 54 indicating the over-time.

A further constructional example of the subject matter of the invention is shown in Fig. 15 in which the type wheel is actuated by a ratchet mechanism.

The type wheel 57 is provided with printing types 59 the figures on which form a consecutive scale of units of the working time, for instance tenth of working hours and the numbering being 00, 0.1, 0.2, 0.3 . . . 1.0 1.1 . . . up to 12.00 indicating 12 working 125 130

hours. The type wheel 57 is fixed to a shaft 58 and it is rotated by means of a two-armed ratchet lever 60 turnably mounted in a pin 61.

The ratchet lever 60 carries at its one arm 5 a pusher pawl 62 which is pressed by means of a spring 63 against pins 64 arranged in a circle on a disc 65 rigidly connected to the type wheel 57. The other arm of the lever 60 is a pawl 66 cooperating with a ratchet disc 67 and is pressed against the latter by means of the spring 68. The disc 67 is rigidly mounted on a shaft 69 driven by a clockwork in the direction of the arrow shown in Fig. 15 and the circumference of the disc is 10 provided with toothed portions 70 and blank 15 portions 71.

During the working time the teeth of one or the other of the toothed portions 70 of the disc 67 cooperate with the pawl 66 and every 20 tooth causes a turning motion of the lever 60 against the influence of the spring 68. Thereby the pusher pawl 62 cooperating with the pins 64 causes a turning movement of the type wheel through a determined angular 25 amount whereupon the pusher pawl 62 is in a position to cooperate with the next pin 64 and so on. The angular movement of the type wheel imparted by each action of the ratchet lever shall occur after every 6 minutes. If I designates the beginning of the 30 working time, for instance 7 ocl. a. m., the blank portion I^a—I^b on the ratchet disc 67 will have reached the pawl 66 of the ratchet lever 60, at 8.48 a. m. after eighteen ratchet 35 movements of the lever 60 and thereby after eighteen step by step movements of the type wheel I, the blank portion I^a—I^b corresponds to the breakfast interval. The ratchet lever 19 is now not operated by the ratchet disc 67 40 and the type wheel is not turned until the first tooth of the toothed portion beginning at I^b has reached the pawl 66 during the further turning motion of the disc 67 under the actuation of the clockwork. With the peripheral extent of I^a—I^b shown in Fig. 15 this 45 will happen at 9 a. m. when the intermittent turning movement of the type wheel starts again. The ratchet lever 60 is again inoperative at 12 ocl. when the beginning of the blank portion II—III of the circumference 50 of the disc 67 which corresponds to the mid-day interval, has reached the pawl 66. At 1.30 p. m. i. e. when the toothed portion starting at III acts upon the pawl 66 the intermittent turning of the type wheel is again 55 effected until 5 ocl. p. m. when the blank portion between IV and I comes to cooperate with the pawl 66. The peripheral extent of a blank portion IV—I corresponds to two 60 hours and this portion may be used for actuating the ratchet lever 60 by screwing a toothed segment to the disc in a similar manner as has been shown in Fig. 4, whereby the type wheel indicates these time units as over- 65 time. In consequence of the blank portions

in the ratchet disc the type wheel is only turned during the proper working time and it indicates the latter.

The toothed portions on the ratchet disc 67 which take into account the intervals in the working time by their peripheral distance from each other may also be detachably secured to a ratchet disc in a similar manner as has been disclosed with reference to Fig. 4 of the drawings, so that the segments might 70 be exchanged for others the toothing of which corresponds to different units of time or shows a different peripheral extent to take 75 into account intervals in the working time of a different duration.

A further constructional example of the indicating device according to the present invention is illustrated in Figs. 16-18 in which a further stamping mechanism or type organ provided with printing types indicating working time in units of a different order to those of the type wheel is arranged to cooperate with the latter in indicating the working time, the printing organs returning into its initial position by the forces effecting an angular movement of the type wheel. 80

If, for instance, the scale on the type wheel indicates tenths of an hour, the scale on the type organ may indicate hundredths of an hour so that with a work involving a comparatively short working time an exact indication of the latter is rendered possible. 95

Referring now to the instrument illustrated in Figs. 16-18 it is of a similar design to that illustrated in Figs. 1-3 as regards the means for causing the step by step movement of the type wheel 1, which is omitted in Fig. 1 for sake of clearness, and the parts are designated with the same reference numbers. In this case it is however assumed that the gear wheel 20 with which the two-winged blade 28 cooperates performs one complete revolution every 36 minutes, so that the type wheel is intermittently turned every six minutes, the printing types on the type wheel 1 indicating thus tenth of an hour. 100

The type organ comprises a lever 73 turnably mounted on a stationary pivot 74 and carrying on the circumferential part of its arc shaped end 75 printing types 76 bearing the figures "0" to "9". The type organ is arranged beside the printing wheel, so that the figures on the type wheel and on the type organ are arranged close to each other. The lever 73 is provided with a laterally extending control arm 77 which carries at its free end a weight 78 and a pin 79 cooperating with a snail 80 fixed to an axle 81 (Figs. 16 and 18). The circumference of the snail 80 is cam shaped and has ten steps 82 at continuously and uniformly increasing radial distances from the axle 81; the snail is rotated in the direction of the arrow shown in Fig. 18. The angular position of the lever 73 varies when the pin 79 cooperates with 115 120 125 130

different steps 82 and each step causes the lever 73 to take up a definite printing position. It is assumed that the axle 81 performs one complete revolution every six minutes, i. e. every tenth of an hour, so that the lever 73 is turned by the cooperation of the pin 79 with the steps 82 every one hundredth of an hour into a different printing position. When the pin 79 has reached the innermost step 82 of the snail 80, in which position of the pin the lever 73 assumes the position shown in Fig. 16 in full lines, the pin and thereby the lever 73 must be returned into its initial position, in which the pin 79 cooperates with the outermost step 82 and the lever 73 is in the position shown in dash and dot lines, in Fig. 16. To this end a pin 83 is provided on the lever 73 and to the axle 29 on which the blade 28 controlling the movement of the type wheel 1 is fixed, a disc consisting of two equal cam-shaped halves 84 is secured. Every six minutes the tip of the blade 28 glides off the flank of a tooth of the gear wheel 30 and the axle 29 performs half a revolution. Thereby the turning cam 84 acts on the pin 13 and displaces the latter whereby the lever 73 is swung in the direction indicated by the arrow in Fig. 16 and the pin 79 is swung off the innermost step 82 into a position to cooperate with the outermost step 82. To ensure a safe engagement with this outermost step a member 85 is provided forming a continuation of the outermost step 82 pivoted at 86 and is operated by a spring 86. When the lever 73 is returned into its initial position and the pin 79 is lifted off the innermost step 82 the member 85 is displaced momentarily against the action of the spring 86 and moves back again when the pin 79 has moved past it and acts as a support to the pin 79 until the latter bears on the uppermost step 82. Thereby the lever 73 is kept in a position in which the type marked with "0" is in the printing position. After the elapse of 1/100 of an hour the snail 80 has been turned so far that the pin 79 drops onto the next step 82 whereby the lever 73 is turned by the weight 78 so that the printing type carrying the figure "1" is in the printing position and so on until the snail 80 has been turned so far that the pin 79 rests on the innermost step 82 of the snail 80 in which case the printing type carrying the figure "9" is in the printing position. The printing organ remains in each intermediate position during an interval amounting to one hundredth of an hour. Then the means for moving the type wheels are released, the blade 28 performs one half of a revolution and the type wheel 1 is turned so that the following printing type indicating one tenth of an hour is in the printing position and the printing organ indicating the hundredth of an hour is simultaneously returned into its initial position. As may be seen in Fig. 17 the printing

types indicate the hours with the figures 100, 200, 500, 600 and so on and the intermediate types bear the figures 5.1, 5.2 and so on. To the figures on the type wheel the figures on the printing types of the organ 73 are joined so that the time on a card will be recorded such as 5.10, 5.11, 5.12 and so on, indicating thus the beginning or the end of a working time with an accuracy of two decimals of an hour.

The intervals in the working time are again taken into account in a similar manner as has been described above with the first constructional example by omitting printing types on the type wheel along peripheral extents which correspond to the duration of these intervals.

In Fig. 19 a modification of the apparatus provided with a printing organ indicating hundredths of an hour is illustrated which differs from the apparatus shown in Figs. 16-18 in the manner in which the printing organ is returned into its initial position. In Fig. 19 only the parts necessary to effect this return movement are shown, the other parts of the apparatus being similar to those illustrated in Figs. 16 and 17 are omitted for the sake of clearness.

The type wheel 1 being again provided with printing types having figures to indicate tenths of hours, is fixed on the shaft 2 and a disc 88 provided with toothed and blank circumferential portions is also fixed to said shaft. The toothed portion I-II corresponds to the forenoon working hours, the blank portion II-III to the noon interval, the toothed portion III-IV to the afternoon working hours and the blank portion IV-I to an interval to make up 12 hours. The pitch of the teeth corresponds to tenths of working hours. The circumference of the type wheel 1 is provided in a similar manner with printing types in the parts I-II and III-IV indicating the working hours, whilst the parts II-III and IV-I have no printing types. The type organ 73 is again turnable about a fulcrum 74 and is turned into ten portions by the action of the rotating snail 80 provided with ten working steps 82 with which a tooth 89 on the free end of the lever arm 77, which is in rigid connection or integral with the lever 73, cooperates. A turning of the snail 80 in the direction of the arrow causes the ten printing types 76 on the arc shaped end of the lever 73 to come consecutively into the operative printing position. In order to return the lever 73 into its initial position after the tooth 89 has moved along the innermost step 82 a tooth 90 is provided on the lever arm 77 adapted to engage with the teeth of the disc 88. The moment the tooth 89 has moved along the innermost step 82, i. e. when one ninth of the hundredth of an hour has elapsed, the type wheel and the disc 88 are moved by the clock-work 21 re-

leased by the blade 28 (Figs. 1 or 16), thereby the tooth 90 is forced out of the space of tooth with which it cooperates and the lever arm 77 and the lever 73 are swung into their 5 initial position in which the tooth 89 rests again on the outermost step 82 of the snail 80. This action is repeated every time the type wheel is turned after the elapse of six minutes or one tenth of an hour. During 10 the intervals in the working hours the printing lever 73 remains in its inoperative position, as the tooth 90 rests on the blank portions of the disc 88 which is at the same radial distance from the shaft 2 as the tips of the 15 teeth of the toothed parts of the disc 88.

Also with this constructional example the toothed parts of the disc 88 may be separate segments exchangeably secured to a disc body. It has been assumed that the disc 88 together 20 with the type wheel 1 performs one revolution in 12 hours, however these parts may also perform one revolution in 18 or 24 hours, whereby the scale indicating the time will have to be modified accordingly.

25 I claim:

1. In a workman's time recorder, a clock work, a type wheel, an operative connection between said type wheel and said clock work, and a scale on said type-wheel indicating 30 units of time, which scale takes into account the intervals in the working time so that the type wheel indicates directly the effective working time.

2. In a workman's time recorder, a continuously driven type wheel having on its circumference a series of type conforming to a continuous scale, which scale is interrupted for the duration of non-working periods.

3. In a workman's time recorder, a continuously stepped printing wheel having a series of successive denominations on its circumference, said series having non-printing portions for non-working periods, a driving train for said wheel, a time train, mechanism 40 between the two trains to control the stepping of said wheel, a pivoted printing member adjacent said wheel for printing fractional denominations of the steps of said wheel, means in the time train to actuate said member and 45 means on the driving train to re-set the member to zero each time said wheel is stepped.

In testimony whereof I affix my signature.
JULIUS BRENDLE.
